UNITED STATES PATENT OFFICE.

PAUL L. SETTLE, OF WASHINGTON, DISTRICT OF COLUMBIA.

AERIAL BOMB.

1,318,926.

Specification of Letters Patent.

Patented Oct. 14, 1919.

Application filed March 21, 1917. Serial No. 156,307.

To all whom it may concern:

Be it known that I, PAUL L. SETTLE, a citizen of the United States, residing at Washington, in the District of Columbia, have invented certain new and useful Improvements in Aerial Bombs, of which the following is a specification.

This invention relates to aerial bombs and more particularly to that type of such devices which are designed to be dropped from an air craft and which are designed to be exploded before reaching the ground surface.

It is the primary aim of the invention to provide a bomb of the class mentioned which may be handled with safety and which may be arranged to explode at any desired predetermined elevation above the ground surface.

Another aim of the invention is to provide an aerial bomb which may be conveniently and very quickly set to explode at the desired elevation and in which the exploding mechanism may embody a second bomb designed to explode upon reaching the ground surface.

The bomb embodying the present invention includes an explosive shell and an exploding mechanism which embraces a spring actuated firing pin designed to be held inactive through the instrumentality of a pilot device while the bomb is falling, the said pilot device, however, being designed to permit actuation of the firing pin when the pilot device reaches the ground surface, and the invention has as another object to provide means for positively holding the firing pin from actuation by its spring while the bomb is being handled, and before it is dropped from the aerial craft. Incidentally, the invention aims to so construct the exploding mechanism that the means provided for positively holding the firing pin inactive will in turn be rendered inactive automatically when the bomb is released or dropped from the craft.

Another aim of the invention is to provide a bomb of the class mentioned which before use may be arranged in compact form so as to occupy but little space.

In the accompanying drawings:

Figure 1 is a perspective view of the bomb embodying the present invention in its condition prior to use;

Fig. 2 is a perspective view of the bomb showing its condition while falling;

Fig. 3 is a vertical longitudinal sectional view through the bomb;

Fig. 4 is a similar view through the lower end only of the bomb and in a plane at right angles to the plane of Fig. 3;

Fig. 5 is a perspective view of the firing pin removed from the bomb.

The bomb proper comprises an explosive shell including a hollow cylindrical body 1 which, at its upper end is interiorly threaded, as at 2, and closed by a concavo convex cap 3 which has a filling opening 4 formed centrally therein and threaded to receive a plug 5 which is preferably provided with a polygonal head 6 having a transverse opening 7 in which may be engaged a hook or other device for carrying the bomb or for suspending the same in position to be dropped. As stated, the cap 3 is concavo convex, the concave side of the cap being presented outwardly and housing the head 6 of the plug 5, in the manner clearly shown in Fig. 3 of the drawings. The body 1 of the shell is interiorly threaded at its lower end, as at 8, and fitted therein is a circular head 9 which is formed upon its upper face with an interiorly threaded annular boss 10 receiving the lower end of a cell 11 in the upper end of which cell there is arranged a detonating cap 12. The boss 10 surrounds an opening 13 formed centrally within the head 9, and fitted within the said threaded lower end of the shell body 1 is another head, indicated by the numeral 14 and formed centrally with an opening 15 located opposite to but of smaller diameter than the opening 13, the heads 9 and 14 being in close contact, as clearly shown in Figs. 3 and 4 of the drawings. The firing pin here-tofore referred to includes a head 16 having a conical upper end 17 designed to strike the detonating cap 12 under conditions to be presently explained, and a stem 18 which is of less diameter than the head 16 and which extends downwardly from the lower end of the head and slidably through the opening 15. When the firing pin is inactive, as shown in Figs. 3 and 4 of the drawings, the lower end of the head 16 thereof will occupy the opening 13 and rest upon the upper surface of the head 14 at the opening 15. A collar 19 is fitted upon the

105

lower end of the stem 18 of the firing pin and is held against upward displacement by a cross pin or the like 20 which is fitted through the said stem, and extending in opposite directions from the collar 19 are arms 21 to the ends of which are connected the lower ends of springs 22, these springs at their upper ends being connected, as at 23, to the head 14. It will be understood that the firing pin may be retracted against the tension of the springs 22 to the inactive position shown in Fig. 3 of the drawings and that when the firing pin is released these springs will immediately act to drive the same upwardly against the detonating cap 12 thus exploding the charge contained within the shell. This charge may be of any suitable and desired form but preferably there is arranged axially within the body of the shell a tubular charge container 24 which may be in the nature of a paper tube and which at its lower end surrounds the cell 11 for the detonating cap 12 and at its upper end communicates with the filling opening 4. It will be understood that any suitable charge of high explosive, indicated by the numeral 25, may be introduced into the container 24 through the filling opening 4. Prior to fitting the cap 3 into place in the upper end of the shell body, the space between the wall of the shell body and the tubular container 24 is filled with shrapnel balls or the like, indicated by the numeral 26.

35 The lower end of the stem 18 of the firing pin is provided with a head 27 having a ball race 28 surrounding the lower end of the stem and having arranged therein bearing balls 29. A yoke having a connecting portion 30 has its said portion formed with a central opening through which the lower end of the stem 18 loosely passes, the underside of the connecting portion of the yoke resting upon the bearing balls 29 whereby the yoke as a whole may have free turning movement about the lower end of the firing pin. It will be observed that the connecting portion of the yoke lies between the head 27 and collar 19. Depending from the portion 30 of the yoke are side portions 31 which at their lower ends are formed with openings or other suitable bearings 32 for the projecting ends of the spindle or reel 33. The side portions 31 of the yoke are resilient and their lower ends may, consequently, be sprung apart so as to permit of the ready insertion into place and removal of the reel 33. Wound upon this reel 33 is a thin cable or other flexible element 34 to the free end of which is connected a pilot 35 which is in the nature of a weight and may be cast solid or may be of hollow formation and filled with shot or the like until the pilot possesses the desired weight, or this pilot may be in the nature of a second bomb designed to be detonated upon striking the ground surface. The pilot 35 is heavier than the shell proper and, consequently, when the bomb is dropped the pilot will fall faster than the shell and the cable 34 will be unwound from the reel 33 until its entire length has been paid out. Any suitable means is provided for retarding the rotation of the reel 33 so as to prevent too rapid unwinding of the cable 34 and this means may consist of a ratchet head 36 at one end of the reel and a pawl 37 mounted upon the adjacent side member of the yoke 30, the pawl being held in engagement with the ratchet head by means of a leaf spring 38.

In order to suitably retard the descent of the bomb there is provided means which will now be described. The retarding means includes upper and lower bands 39 and 40 each of which is formed in two sections, the bands being disposed to surround the body of the shell in the manner clearly shown in Figs. 1 and 2, the corresponding ends of the sections of the two bands being connected by portions 41 and the meeting ends of the sections of each band having apertured ears 42 through which are passed clamping bolts 43. Pivotally connected, as at 44, to the band 39 at suitable intervals in the circumference thereof are retarding wings 45 which, prior to the use of the bomb, depend beside the body of the shell and more or less closely fit the same, the wings being suitably curved for this purpose. In order that the wings may be held properly distended during the downward flight of the bomb, as shown in Figs. 2 and 3 of the drawings, a brace is provided for each wing and comprises a section 46 pivotally connected to the lower band 40 and a section 47 pivotally connected, as at 48, to the inner side of the respective wing, the sections at their meeting ends being mutually connected by a rule joint 49.

In order that the firing pin may be positively held in inactive position prior to the time of actually using the bomb or dropping the same, there is provided a detent 50 having at one end a tooth 51 which is designed to engage behind a shoulder 52 formed at the lower end of a seating recess 53 in turn formed in the side of the stem 18 of the firing pin. A spring 54 is connected to the detent 50 and to the head 14, as clearly shown in Fig. 4 of the drawings and after retracting the firing pin against the tension of the springs 22 the detent 50 may be drawn against the tension of the spring 54 into engagement in the recess 53 with its lug 51 seating behind the shoulder 52. Then when the firing pin is released and is drawn upwardly by the springs 22, its upward movement will be limited by the engagement of the detent 50 against the underside of the head 14. The bomb may then be

handled with safety. However, if it is desired to further insure against accidental explosion of the bomb a short wire or the like, indicated by the numeral 55, may be 5 connected to the detent 50 and led through an opening 56 formed in the stem 18 opposite the recess 53, and then connected to an eye 57 upon the underside of the head 14. Prior to dropping the bomb it will, of 10 course, be necessary to sever this wire. When the bomb is dropped the pilot 35 being heavier than the shell of the bomb will fall more rapidly and, therefore, the cable 34 will be unwound until its entire length has 15 been paid out. It will be understood that the pilot 35 will maintain the cable 34 in taut condition and, therefore, the firing pin will be held retracted. Furthermore, the pull upon the cable 34 will cause the 20 firing pin to move downwardly to such an extent as to cause the detent 50 to clear the head 14 whereupon the spring 54 will cause the detent to leave the recess 53 so that it will be inactive and will not 25 interfere with movement of the firing pin in the direction of the detonating cap 12. As soon as the pilot 35 reaches the ground surface, however, the cable 34 will be slackened and the springs 22 will drive the firing pin 30 into contact with the detonating cap 12, thereby exploding the shell. The length of the cable 34, of course, determines the elevation at which the bomb will be exploded and it will be understood that a number of 35 the reels or spools 33 may be carried having different lengths of cable wound thereon and one or another of the reels may be selected depending upon the elevation at which it is desired to explode the bomb.

40 By reference to Figs. 3 and 4 of the drawings it will be observed that the firing mechanism projects below the lower end of the shell body 1 and when the bomb is being dropped is exposed so that if, for any reason, slackening of the cable 34 does not serve 45 to explode the bomb, this will be sure to occur when the firing mechanism strikes the ground surface as then the firing pin will be positively driven upwardly into contact 50 with the detonating cap 12. In order to protect the firing mechanism prior to preparation of the bomb for dropping, and also for the purpose of further insuring against accidental explosion of the bomb, a hollow 55 conoidal safety cap 58 is removably threaded or otherwise fitted to the lower end of the shell body 1 and when in place completely incloses and houses the firing mechanism.

Having thus described the invention, 60 what is claimed as new is:

1. In a bomb of the class described, an explosive shell, a firing element, a flexible element carried thereby and arranged when taut to exert a direct longitudinal pull on 65 the firing element and hold the same in-

active and when slackened to release the firing element for actuation, means for actuating the firing element, and a weight element connected with the said flexible element.

70

2. In a bomb of the class described, an explosive shell, means for retarding the travel thereof, a firing pin, means tending to actuate the firing pin, a flexible element carried by one end of the firing pin, and a weight connected with the said element.

75

3. In a bomb of the class described, an explosive shell, a firing pin slidably mounted in the shell, means tending to actuate the said pin, a flexible element carried by the lower end of the firing pin and arranged when taut to maintain the firing pin in inactive position and when slackened to release the same for actuation, and a weight connected with the said flexible element and being heavier than the said shell.

80

4. In a bomb of the class described, an explosive shell, a firing pin, means tending to actuate the firing pin, a detent for holding the firing pin inactive, means tending to render the detent inactive, a flexible element connected to the firing pin and arranged when taut to retract the firing pin and permit the last-mentioned means to render the 90 detent inactive whereby to release the firing pin for actuation when the said flexible element becomes slack.

95

5. In a bomb of the class described, an explosive shell, a firing pin slidably mounted in the shell, a spring tending to actuate the firing pin, a flexible element carried by the lower end of the firing pin and arranged when taut to exert a direct longitudinal pull upon the firing pin to hold the same retracted against the tension of the spring, and a 100 pilot weight connected with the said flexible element.

105

6. In a bomb of the class described, an explosive shell, a firing pin mounted slidably, a spring tending to actuate the firing pin, a flexible element carried by the firing pin and arranged when taut to exert a direct longitudinal pull upon the firing pin to hold the same retracted against the tension of the spring, a pilot weight connected 110 with the said flexible element, and means operable to positively engage the firing pin above its lower end and hold it against actuation under the influence of the said spring.

115

7. In a bomb of the class described, an explosive shell, a firing pin mounted for longitudinal sliding movement in the shell, means tending to actuate the said pin, a reel hung on the lower end of the pin, a flexible element wound upon the reel and arranged when taut to hold the firing pin inactive, a weight connected with the said flexible element, and means for retarding the rotation 120 of the said reel.

125

8. In a bomb of the class described, an 130

- explosive shell, a firing pin, means tending to actuate the said pin, a reel hung on the lower end of the pin, a flexible element wound upon the reel and arranged when 5 taut to hold the firing pin inactive, a weight connected with the said flexible element, means for retarding the rotation of the said reel, and means for retarding the travel of the shell, the weight being heavier than the 10 said shell.
9. In a bomb of the class described, an explosive shell, a firing element, a spring connected with the shell and with the firing element tending to move the firing element 15 in a direction to explode the charge, a reel separated from the firing element, a flexible element wound upon the reel and arranged when taut to exert a pull upon the firing element through the said reel and thereby 20 hold the element retracted against the tension of the spring, and a pilot weight connected with the said flexible element.
10. In combination, a main bomb, an auxiliary bomb located at a predetermined distance 25 from the main bomb, and mechanism to explode both the main bomb and the auxiliary bomb upon contact of the auxiliary bomb with the earth, whereby the main bomb is exploded while still in the air, substantially as described.
11. In combination, a main bomb, an auxiliary bomb, said auxiliary bomb being normally located adjacent to the main bomb, means to separate said main and auxiliary 35 bombs to a predetermined distance during the flight of the main bomb, and means to explode both bombs upon contact of the auxiliary bomb with the earth, substantially as described.
- 40 12. An ordnance device comprising a plu-

rality of spaced bombs and detonating means extending between the two bombs for exploding one bomb when the other bomb explodes.

13. An ordnance device comprising two 45 bombs, means joining the two bombs together in spaced relationship and means for exploding both bombs when one bomb strikes an obstruction.

14. An ordnance device comprising a plurality of spaced bombs, means joining the bombs together, the device being so shaped and weighted that in flight one bomb will travel ahead, and detonating means for exploding the bombs when the forward bomb 55 strikes.

15. An ordnance device comprising an elongate member, a bomb at each end of the member, the device being so shaped and weighted that in flight one bomb will travel 60 in advance, means for detonating the forward bomb when it strikes, and means responsive to said means for detonating the other bomb.

16. In a bomb of the class described, the 65 combination of an explosive shell, a head secured in the lower end of the shell, a firing pin mounted for sliding longitudinal movement in the said head, a spring secured to the said head and connected to the firing pin to actuate the same to explode the shell, a yoke swiveled on the lower end of the firing pin, a reel carried by said yoke, a cable wound on the reel, and a pilot carried by said cable and normally holding the 70 same taut whereby to retract the firing pin in opposition to the spring acting thereon.

In testimony whereof I affix my signature.

PAUL L. SETTLE. [L.S.]
